SYSTEM FOR ELIMINATING INTERFERENCE

Filed Feb. 9, 1924

UNITED STATES PATENT OFFICE.

JOSEPH O. MAUBORGNE AND GUY HILL, OF WASHINGTON, DISTRICT OF COLUMBIA.

SYSTEM FOR ELIMINATING INTERFERENCE.

Application filed February 9, 1924. Serial No. 691,559.

To all whom it may concern:

Be it known that we, JOSEPH O. MAUBORGNE and GUY HILL, citizens of the United States, residing at Washington, District of Columbia, have invented certain new and useful Improvements in Systems for Eliminating Interference, of which the following is a specification.

This invention relates to the art of eliminating undesired frequencies in radio receiving circuits and discloses a new and useful system for accomplishing this purpose.

In our copending applications Serial Nos. 383,720, 459,530, 481,334 and 401,746, we have described the construction and use of a coil which we designated as a resonance wave coil for use as an antenna or collector of high frequency energy in connection with receiving apparatus.

We have found that the same type of wave coil may be employed to absorb energy from a lead connected to the receiving circuit to such a marked degree that if the wave coil be adjusted to any given frequency which is undesired, the energy of this frequency will be eliminated by the wave coil, so that the receiving apparatus will be substantially free from the undesired frequency. In other words, this wave coil, when properly connected, has been found to accomplish the same purpose as the so-called "wave trap."

It is characteristic of the apparatus we propose that it is extremely simple in operation as the inductance and capacity of the wave coil, or "open circuit wave trap"—in the simplest form of our apparatus remain fixed, and elimination of the undesired frequency is accomplished solely by moving a single variable electrical connection along the wave coil until the undesired signals are reduced to a minimum, the single lead making variable connection to the coil being connected to the same point of the circuit from which undesired signals are to be eliminated. This is an improvement over existing wave trap circuits which consist of lumped inductances and capacities either or both being variable and in the form of a closed circuit.

It is a further characteristic of our invention that a plurality of such coils may be employed, and so connected to a single circuit as to simultaneously eliminate two or

more undesired frequencies, the arrangement becoming an electric filter permitting band tuning if a sufficient number of coils and proper arrangement thereof be made.

A resonance wave coil, suitable for the purpose of this invention, consists, in one of its forms, of a coil preferably uniformly wound with wire to form of a helix, in the form of an open circuit, having fixed distributed inductance and capacity of such values that the coil will respond to a wide range of frequencies. The coil is provided with a single adjustable electrical connection so that connection can be made to any desired element of the wave coil. Instead of a variable connection to the coil, this connection can be fixed or connections be made to taps and fine or vernier adjustment made by means of an adjustable metallic extension electrically connected to one or both ends of the coil.

In our copending applications, referred to above, more detailed information has been given concerning the construction and characteristics of these coils.

Our invention will be best understood by reference to the following description taken in connection with the accompanying drawings in which:—

Fig. 1 is a diagrammatic view of one form of the device used for the elimination of high frequencies.

Figure 2 is a diagrammatic view showing the open circuit wave trap connected in a normal way to an ordinary radio receiving system.

Figure 3 is a diagrammatic view showing the method of connecting our device to an ungrounded loop receiving apparatus.

Figure 4 is a diagrammatic view, similar to Figure 3, except that the receiving apparatus is grounded, and the wave trap is connected to the ground lead.

Figure 5 is a diagrammatic view showing two conductors connected to the same receiving apparatus, an open circuit wave trap being connected to each of the conductors.

Figure 6 is a diagrammatic view, similar to Figure 2, except that a plurality of wave traps is connected to the same conductor.

Figure 7 shows details of construction of the form of wave coil indicated diagrammatically in all of the preceding figures.

Referring more particularly to the draw-

ings, 1 represents a conductor through which high frequency currents pass to a receiving apparatus, which is connected to the conductor 1. 3 represents a wave coil 5 and 4 a single lead connecting electrically the wave coil to the conductor 1 at point 5. 6 is a slider electrically connected to lead 4, so that the conductor 1, by means of lead 4, can be connected to any desired point on 10 the wave coil. 7 is a small metallic extension electrically connected to one end of the wave coil 3. The length of the extension can be varied by operation of the knob 8, for the purpose of varying the constants of 15 the coil, and operates as a vernier affording a means of accurate tuning.

We have found that if, in the conductor 1, there are flowing two currents of different frequencies, that by means of the apparatus 20 shown, one of these frequencies can be received and the other eliminated. Thus the undesired frequency will not cause any appreciable effect to be produced in the receiving apparatus.

25 Several methods of procedure can be carried out in order to eliminate the undesired frequency. The methods will vary in details depending upon actual conditions. If the wave coil has been calibrated and the wave 30 length of the interfering signal is known, the wave coil should be connected to the conductor 1, and slider 6 moved to the position that will bring the wave coil in tune with the interfering frequency. The receiving 35 apparatus 2 should then be tuned in the ordinary manner and it will be found that little or no interference will be present, depending upon the percentage of separation of the two frequencies. A slight retuning 40 of the wave coil and also of the receiving apparatus will at times produce further reduction of the interfering signal.

If the wave length of the interfering signal is not known, or the wave coil has not 45 been calibrated, the following procedure should be used. The receiving set should be tuned to the desired frequency with the wave coil disconnected from conductor 1. Then the wave coil should be connected to the conductor 1 at point 5 and the slider 6 moved until the interfering signal vanishes or is reduced to a minimum. In some cases, retuning of receiving apparatus 2 will be found necessary after connecting wave coil 50 3 and lead 4 to conductor 1.

In both of the methods described, final 60 exact tuning of the wave coil may be made by adjusting the length of the metallic extension 7, which acts as a vernier. When extension 7 is used for exact tuning, the slider 6 does not need to be adjusted as accurately as when wave coil 3 is not provided with the extension described.

Instead of having a slider, such as 6, 65 which can make contact with each and every

turn of the coil, a series of taps may be brought out from the coil, to any one of which lead 4 can be connected, to provide approximate tuning, the exact tuning being finally accomplished by varying the extension 7. Extension 7 is not an essential part 70 of the open circuit wave trap described but may be added for convenience in obtaining exact tuning.

Figure 2 is similar to Figure 1. In this figure the conductor 1 is a lead connecting antenna A to receiving set 2. Receiving set 2 is connected to ground G by means of lead 1', if desired, altho it is to be noted that the wave coil 3 will function as a wave trap 80 whether receiving apparatus 2 be grounded or not.

Symbols 3 to 8 represent similar apparatus to that indicated by the same symbols in Figure 1 and perform the same functions as 85 described in the specification pertaining to that figure.

The operation of the apparatus for eliminating a single interfering frequency is identical with that described for Figure 1. 89

Figure 3 shows the method of connecting the open circuit wave trap to a loop antenna and associated receiving apparatus. 1 is, in this case, the conductor forming part of the circuit of the loop antenna. 2 represents the receiving apparatus which combines with coil 1 to form an ordinary loop receiver, which is well known in the art. 10 and 11 are the terminals of the receiving apparatus to which the loop 1 is connected. In receiving sets where one terminal of the loop is connected to the grid of a vacuum tube, this terminal in the figure is represented by 10. We have found that it is preferable to connect lead 4 from wave coil 3 to a point 5 as near as practicable to or coincident with, terminal 10 which we have designated as the grid terminal of the receiving apparatus 2.

Symbols 3 and 4 to 8 inclusive represent 110 similar apparatus to that indicated by the same symbols in Figure 1, and perform the same functions as described in the specification pertaining to that figure.

The operation of the apparatus for eliminating a single interfering frequency is identical with that described for Figure 1. 115

Fig. 4 represents a grounded loop receiving circuit. 1' represents a lead connecting terminal 12 of loop receiving apparatus 2 120 to ground. Terminal 12 is ordinarily electrically connected with the filament circuit, where a vacuum tube detector is used. Where a loop receiving set is connected to ground as shown in this figure, in many 125 cases, an increase in signal strength results, but considerable interference may be introduced through the ground lead 1'. We have found that by connecting the open circuit wave trap herein described to a point 5 on 130

said ground lead 1', that the effect of the interfering frequency on the receiving apparatus 2 can be eliminated.

Symbols 1 to 4 inclusive and 6 to 11 inclusive represent similar apparatus to that indicated by the same symbols in Fig. 3, and perform the same functions as described in the specification pertaining to that figure and to Figure 1.

10 The operation of the apparatus for eliminating a single interfering frequency is identical with that described for Figure 1.

Figure 5 represents two conductors 1 and 1' such as a pair of wires that might be used in line radio, wired wireless, or carrier current telegraphy or telephony, said conductors supplying the high frequency current to suitable receiving apparatus 2. In case it is desired to eliminate a single interfering frequency which might be present on each of said conductors 1 and 1', two open circuit wave traps are used, one connected to each of the conductors 1 and 1' respectively as shown in the figure, where 3 and 3' represent similar wave coils, and the other symbols as 7 and 7' represent similar details of the similar apparatus. 13 and 14 are the terminals of the receiving apparatus 2, connected to conductors 1 and 1' respectively.

Symbols 3 to 8 inclusive and the corresponding symbols 3' to 8' inclusive represent apparatus similar to that indicated by the same symbols in Figure 1 and perform the same functions as described in the specification pertaining to Figure 1.

The operation of the apparatus for eliminating a single interfering frequency consists in adjusting each of the two open circuit wave traps as described for a single wave trap in specification referring to Figure 1.

Figure 6 represents the use of a plurality of wave coils 3, 3' and 3'' all connected to a conductor 1 through which high frequency currents pass to receiving apparatus 2, for the purpose of eliminating a plurality of interfering frequencies.

The symbols used for the respective wave coils correspond with each other and with those used in Figure 1, and the apparatus is similar to and performs the same functions as described in the specification pertaining to Figure 1, except that a plurality of frequencies can be eliminated by the arrangement shown in Figure 6.

The operation of the apparatus for eliminating a plurality of interfering frequencies consists in separately adjusting each of the open circuit wave traps to eliminate one of the interfering frequencies as described for a single wave trap in the specification relative to Figure 1.

Referring specifically to Figure 6, in case there are only two interfering frequencies,

and one of these is very powerful, two of the wave traps shown may be adjusted to the same frequency—that of the strong interfering signal, while a third may be adjusted to eliminate the weaker frequency. 70

Figure 7 shows details of construction of the wave coil shown in Figures 1 to 6 inclusive. 3 represents the winding of the coil proper, a section of which is shown as removed to permit explanation of internal construction. This winding is associated with a slider 6 supported on insulating strip 20, which is mounted on insulating core 21, and adjacent to winding 3 which is wound on core 21. Part of core 21 is also shown 80 as removed to permit explanation of interior construction. 7, is the extension in the form of metal ribbon electrically connected to one end of coil, 3, at point marked 22. 23 represents a metal case in which strip 7 coils up 85 under action of spring not shown in drawing which is connected at point 24 to end of strip 7, and the other end of said spring is connected electrically and mechanically to case 23, which as before stated is in electrical connection with coil 3 at point 22. Strip 7 at its outer end is connected to the tip 25 of an insulating rod, 26, which passes through a guide 27 in the end of rod 26, shown as point 28 in the figure, is attached 90 to an endless cord 29 on pulleys 30 and 31 which have their shafts turning in bearings which are permanently fixed to core, 21. Pulley 30 has its movable shaft extended through core 21 terminating in knob 8. 100

By turning knob 8, string 29 is made to extend or withdraw rod 26 from core 21, thereby causing metallic strip 7 to extend, or coil up within case 23, thereby permitting continuous fine adjustment of the constants 105 of the coil.

While the above details show a form of coil which we have found satisfactory in operation, various other modifications and variations of the device could be employed 110 which would function in a similar manner.

While in the foregoing drawings and specifications we have indicated only one physical form of an open circuit wave trap, we do not confine ourselves to the use of a wave coil of the particular form indicated. In fact, wave coils of other forms, some of which are indicated in our copending applications hereinbefore referred to might be employed. Similarly while we have indicated in the specifications and drawings herewith that each of the wave coils is provided with a variable metal extension, as before stated, this extension is an aid in sharp tuning but is not absolutely necessary for successfully carrying out of our invention. Also, while in the drawing and specifications herewith we have shown the open circuit wave trap connected to certain specific elements of circuits we do not limit ourselves 125 to

to the exact arrangements shown, as, due to complicated and various types of receiving circuits it might be desirable to attach our form of wave trap to other elements than those which we have indicated.

While we have found that wave coils constructed and utilized as wave traps as shown and described in the accompanying figures and drawings have functioned in an entirely satisfactory manner, we have also obtained satisfactory operation by having the wave coil enclosed in a metal case or shield, such shielding in certain cases being used to prevent interaction between adjacent coils or between coils and receiving apparatus. We have not shown such shields in the above figures as we consider them a refinement not essential for the successful operation of our invention.

While for the sake of simplicity in the majority of the figures we have shown only one wave trap, it is to be understood that any desired number of traps can be used in any of the combinations as shown diagrammatically in Figure 6.

Having thus described our invention, we claim:

1. A system for eliminating undesired high frequencies in receiving systems, comprising a conductor carrying two different frequencies, means for receiving signals corresponding to the desired one of these frequencies, an open circuit wave trap in the form of a resonance wave coil having distributed inductance and capacity, said wave coil being connected by a single lead, said conductor carrying high frequency energy to the receiving apparatus, means for selecting the element of the wave coil to which said single lead is to be attached so that said wave coil will eliminate the effect of the undesired frequency upon the receiving apparatus.

2. A system for eliminating undesired high frequencies in receiving systems, comprising a conductor carrying two different frequencies, means for receiving signals corresponding to the desired one of these frequencies, an open circuit wave trap in the form of a resonance wave coil having distributed inductance and capacity, said wave coil being connected by a single lead, said conductor carrying high frequency energy to the receiving apparatus, means for selecting the element of the wave coil to which said single lead is to be attached, and means for varying the constants of the coil so that said wave coil will eliminate the effect of the undesired frequency upon the receiving apparatus.

3. A system for eliminating undesired high frequencies in receiving systems, comprising a conductor carrying two different frequencies, means for receiving signals corresponding to the desired one of these

frequencies, an open circuit wave trap in the form of a resonance wave coil having distributed inductance and capacity, said wave coil being connected by a single lead, said conductor carrying high frequency energy to the receiving apparatus, means for selecting the element of the wave coil to which said single lead is to be attached, and means for varying the constants of the coil so that said wave coil will eliminate the effect of the undesired frequency upon the receiving apparatus, said means comprising an extensible metallic body electrically connected to one end of said wave coil, and means for varying the effective electrical dimensions of said metallic body.

4. In an apparatus for eliminating undesired high frequencies in receiving systems, a wave coil consisting of an insulating tube, a single layer winding of insulated wire in the form of a helix wound thereon, said wire being uninsulated in part to permit contact to be made therewith by a slider provided with a terminal for connecting said coil to the remainder of the receiving apparatus, an extensible strip of metal electrically connected to one end of said coil, and means for coiling and extending said strip of metal in prolongation of said wave coil.

5. A system for the reception of radio signals comprising in combination an antenna circuit, a receiving circuit coupled with said antenna circuit, a resonance wave coil, and an independent connection from the said antenna to a point on said resonance wave coil, said connection on said wave coil being adjustable.

6. A system for the reception of radio signals comprising in combination a wire system over which high frequency signals are received, a receiving circuit coupled with said wire system, a resonance wave coil, and an independent connection from the said wire system to a point on said resonance wave coil said connection on said wave coil being adjustable.

7. A system for the reception of radio signals comprising in combination an antenna circuit, a receiving circuit coupled with said antenna circuit, a resonance wave coil, said resonance wave coil consisting of a conductor having distributed inductance and capacity on which standing waves are developed, and an independent connection from said antenna to a point on said resonance wave coil, said connection on said wave coil being adjustable.

8. A system for the reception of radio signals comprising an antenna circuit, a receiving circuit coupled with said antenna circuit, a resonance wave coil having means whereby it may be brought into resonance for the frequency of the undesired interfering signal for absorbing the energy of the

undesired signal, and an independent connection from the said antenna to a point on said resonance wave coil, said connection on said wave coil being adjustable.

- 5 9. A system for the reception of radio signals comprising an antenna circuit, a receiving circuit coupled with said antenna circuit, a resonance wave coil, and a separate connection from said antenna to a point on
- 10 said resonance wave coil, said separate connection being adjusted so that said wave coil operates as a wave trap for a particular signal frequency which it is desired excluded from the receiving system.
- 15 10. A system for the reception of radio

signals comprising an antenna circuit, a receiving circuit coupled with said antenna circuit, a plurality of resonance wave coils, separate connections independent one from the other between said antenna to points on each of said resonance wave coils, each of said connections being independently adjustable whereby each of said resonance wave coils serves to absorb the energy of a separate signalling frequency. 20 25

In testimony whereof we affix our signatures.

JOSEPH O. MAUBORGNE.
